UNITED STATES PATENT OFFICE.

LUTHER COBB, OF BEDFORD, INDIANA, ASSIGNOR OF ONE-HALF TO FRED E. JACKSON
AND ONE-HALF TO JAMES D. MARTIN, BOTH OF BEDFORD, INDIANA.

MANIFOLD CONSTRUCTION FOR EXPLOSION-ENGINES.

1,099,842.

Specification of Letters Patent.

Patented June 9, 1914.

Application filed June 23, 1913. Serial No. 775,342.

To all whom it may concern:

Be it known that I, LUTHER COBB, a citizen of the United States, residing at Bedford, in the county of Lawrence and State of Indiana, have invented a new and useful Manifold Construction for Explosion-Engines, of which the following is a specification.

The present invention relates to improvements in manifold constructions for explosion engines, one object of the invention, being the provision of a manifold construction, in which the intake manifold is disposed within the exhaust manifold, and has a plurality of branches led thereto, whereby a volatile and a less volatile explosive fluid to be converted into carbureted air may be properly directed into the intake ports of the engine, the heated exhaust manifold consisting in the vaporization of the less volatile fluid, so as to provide the necessary and desirable carbureting or vaporizing thereof before the introduction into the explosive engine.

A further object of the present invention is the provision of means whereby two characters of carbureted air may be supplied to the explosive engine and whereby the introduction of the explosive charge may be regulated.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a vertical sectional view through the intake and exhaust manifold of the present device with the cylinders of an explosion engine in elevation. Fig. 2 is a top plan view of an engine with the present manifold construction in horizontal section along the portage line of the cylinder.

Referring to the drawings, the numerals 1 and 2 designate the forward two and rear two cylinders of an explosion engine, such two cylinders, as illustrated, being cast *en bloc* and provided as shown, with the intake ports 3, 4, 5 and 6 and the exhaust ports 7, 8, 9 and 10. As clearly shown in Fig. 1,

the exhaust ports of the respective cylinders are the outer ports, while the intake ports are disposed between the two exhaust ports of each pair of cylinders and therefore constitute the inner ports.

The exhaust manifold 11 is connected to both cylinder members so as to embrace the ports 7, 8, 9 and 10 and thus receive the exhaust gases from all cylinders of the engine, while in order to provide a means for assisting in the vaporizing of the mixture admitted to the respective ports 3, 4, 5 and 6, the two intake manifold branches 12—12' are disposed so that the greater portion thereof are enveloped by the exhaust manifold 11 while the inner terminals of the branches 12—12' surround the respective ports 3—4 and 5—6 so that at the proper time the explosive charge is admitted through such ports to the cylinders of the engine.

This particular manifold construction is especially adapted for use in connection with two fuel supplies, as for instance gasoline which is the volatile fluid most often used and also with kerosene, which being a less volatile fluid cannot be used to primarily start the engine. In order to provide a means therefore to permit the starting of the engine by the employment of a carbureted air, formed from gasoline, and after the branches 12—12' have been heated due to the exhaust gases passing through the manifold 11, and therefore permitting the employment of kerosene as the main explosive agent, two branches 13 and 13' are in communication at the port 14 with the two branches 12—12'. In order to regulate the port 14, the cone valve 15 carried by the threaded stem 16 is mounted at the junction 17 of the two branches 13—13' and is thus movable to and from the port 14.

Connected to the lower end of the branch 13 is a gasoline supplying carbureter 18, which in the present instance is simply shown diagrammatically, but is intended to represent any form of carbureter for supplying carbureted air from a gasoline supply to an explosive engine. A butterfly valve 19 is employed to limit the amount of carbureted air supplied to the branch 13.

Connected to the inlet end of the branch 13' is a kerosene supplying member 20, which is indicative of any form of kerosene carbureting means that may be em-

ployed, the same being provided with a butterfly valve 21 to limit the amount of explosive charge supplied to the branch 13'.

From the foregoing description, taken in connection with the drawings, it is evident that by the employment of the gasoline carbureter 18, that the engine may be started as is the usual practice, the butterfly valve 21 being closed so as to prevent the introduction of any of the kerosene charge into the branch 13'. As soon as the engine is running and has become sufficiently heated, the exhaust charge through the manifold 11 having heated the branches 12-12' of the intake manifold, the butterfly valve 21 is opened and the kerosene supplying medium is connected so that the carbureted air composed of air and kerosene is directed through the branch 13' into the intake branches 12-12'. When the engine is operating properly, the butterfly valve 19 is closed, and then the only supply for the carbureted air is from the kerosene supplying member 20. Thus with the present structure, the branches 12-12' constitute the heated vaporizing chamber for the carbureted air, and provide a means, whereby the volatile and less volatile fluids may be used to advantage, the volatile fluid being used as the primary starting fluid, while the less volatile fluid is employed as the main fluid.

If still desired, the butterfly valves 19 and 21 may be so connected, that as the valve 19 is gradually cut out the valve 21 will be gradually cut in, and vice versa. By this means, the mixture of carbureted air may be tem-

pered down from a carbureted air consisting entirely of gasoline and air to an intermediate carbureted air composed of gasoline and air and kerosene and air, to the final main mixture of kerosene and air. Thus the proper operation of an explosion engine with the two fuels, as indicated will be rendered more efficient, it having been discovered that the less volatile fluid must be heated so as to produce the best possible vaporization and mixture for explosion engines.

What is claimed is:

The combination with an explosion engine having an exhaust manifold, of an intake manifold having the greater portion thereof incased by the exhaust manifold and provided with a port intermediate its ends and through the under side thereof, two carbureted air supplying branches both leading to said port, portions of the branches being joined together below the port, a valve stem mounted in the portion of the branches below the port and operable from the outside, a conical valve carried by the stem within the branches and manifold for movement to and from the port, and two explosive mixture forming devices, one connected to each branch.

In testimony that I claim the foregoing as my own, I have hereto affixed my signature in the presence of two witnesses.

LUTHER COBB.
